PROJECTILE

Emil Leussler, Nuremberg, Germany, assignor, by
mesne assignments, to Remington Arms Com-
pany, Incorporated, Bridgeport, Conn., a corpo-
ration of Delaware

Application April 26, 1933, Serial No. 667,999
In Germany December 9, 1931

8 Claims. (C.I. 102—26)

The so-called divided casing projectiles, which are used for hunting purposes, are intended to stop the game as far as possible on the spot where it is hit, or at least to obtain an exit wound in order to insure a good blood track for searching for the game.

In order to obtain this result, very many different proposals have been made for the construction of such projectiles. Such proposals include inserting a transverse partition in the projectile casing, with the object of insuring that the front part of the projectile shall shatter on striking and penetrating the body of the game, and of retaining intact as far as possible the rear part 15 of the projectile with its lead filling in order to secure penetration and an exit wound.

The insertion of a continuous transverse partition in the projectile casing involves difficulties of manufacture and increase in cost, and likewise 20 prevents the use of nickel plated sheet metal as a casing or jacket material.

To simplify and facilitate the insertion of the partition, the jacket has been made in two parts, but this weakens the projectile to such an extent 25 that it may be distorted or broken on passage through the rifle barrel.

It is the object of the present invention to eliminate these disadvantages and to provide a simple, rugged, effective and accurate projectile having one part, preferably the point, which is readily deformed, flattened or even disrupted on impact, and another part, preferably the heel, which is not disrupted with the point but continues to advance as a unit, thereby insuring deep and effective penetration. This is in part accomplished by forming a partition from the jacket itself, an annular fold being made at a suitable 35 point in the jacket, which fold has its sides in contact with each other, and has an internal 40 diameter of such dimensions that escape or scattering of the rear part of the projectile is prevented.

The invention likewise comprises a method of making the projectile by forming the annular fold in the jacket after the core metal for the rear or heel part of the projectile has been pressed into place. The core metal for the front part of the projectile is not pressed in until after the formation of the said fold, so that the partition or fold 45 constitutes the plane of separation of the two projectile cores, which cores may be of different hardness.

A projectile is thereby formed which has a one-piece casing provided in a simple manner with 50 an internal transverse partition which serves to

retain in position the projectile-filling in the rear portion of the casing, so that the projectile has a considerable penetrating power and can produce an exit wound, while the front part of the projectile is so constructed that it is shattered on striking and penetrating the body of the game.

The manufacture of the projectile is very simple and cheap because the internal flange-like annular wall can be made very easily by providing the projectile casing, which previously has been provided with the rear half of the filling, with a peripheral groove and then upsetting longitudinally the projectile casing until the groove is compressed to form an inwardly-projecting annular collar, which insures the internal sub-division of the projectile chamber and also determines the bursting zone. On the exterior of the projectile casing at the position of the internal annular collar, there is seen only a circular slit, since in the upsetting operation the initial groove is completely closed.

One typical form of projectile embodying the invention is shown in the accompanying drawing, wherein:

Fig. 1 is a longitudinal section of an empty projectile jacket.

Fig. 2 is a section showing the same jacket with the metal of the heel core or core section in place.

Fig. 3 is a section showing the jacket with the heel core and the groove from which the partition is formed.

Fig. 4 is a section showing the partition, folded inwardly from the jacket wall upon the heel core.

Fig. 5 is a section of the finished projectile.

Fig. 6 is an elevation of the finished projectile.

The projectile casing or jacket, which in the constructional example has a closed base but may be provided equally well with an open base, is first filled to a suitable height with a lead charge 2, and an annular groove 3 is pressed in above said lead charge. By longitudinal upsetting of the jacket the sides of the groove are pressed inwardly, closing the groove and forming an inwardly projecting flat annular collar 3', which thus divides the projectile chamber. The front projectile chamber, which is still empty, is then likewise provided with a lead filling or point core 4, and the tip and base portion of the projectile are contracted or formed, so that the finished projectile shown in Figs. 5 and 6 is obtained. The inwardly projecting annular collar or fold determines the bursting or shattering zone and,

in addition, prevents the heel core from being forced forward. The said heel core 2 preferably consists of hard lead, while the point core 4, which is adapted to be flattened or shattered on impact, may be of soft lead.

Upon striking a target such as the body of an animal the velocity of the projectile point is abruptly and greatly reduced, but due to its momentum the heavy heel section tends to maintain its velocity, with the result that the point is flattened or spread, and its jacket torn apart. If the velocity on impact is high and/or the target is hard (e. g. heavy bone) the point section may be completely disrupted. Such disruption, however, is completely stopped by the fold or annular partition 3', which not only affords a supplemental coverage and support for the heel core 2, but likewise definitely limits the tearing of the jacket metal, so that the heel section continues to move forward and penetrate the target. This effect is augmented when the heel core is of harder metal than the point core. In actual practice the point core is often completely dispersed, and the point jacket is frequently completely sheared off at the angle where it joins the fold 3', the heel section of the projectile with the fold 3' remaining intact. If the velocity is lower, and/or the target is flesh rather than bone, the point section may be merely flattened or "mushroomed", and the projectile as a whole continue to advance. Adequate penetration of all possible hunting targets by projectiles having a wide range of velocities is thus insured.

As shown in the drawing, the fold 3', which is integral with the jacket 1 and formed therefrom by the sequence of simple operations heretofore described, is preferably so located as to provide both a heel section and a point section of substantial size, and likewise projects inwardly from the jacket a sufficient distance to effect a substantial separation between the heel and point cores. Applicant has thus in effect combined two projectiles in one. The point section is a readily deformable projectile which mushrooms on impact with flesh, and the heel sections is a difficultly deformable projectile which penetrates hard bone. Applicant thus realizes the ideal of a projectile which produces the desired effect on the game, regardless of the range or the part of the animal which is struck.

The new form of projectile or shell may also be employed, within the scope of the invention, for explosive projectiles, signalling projectiles and the like, wherein use is made of partitioned casings.

What is claimed is:

1. A projectile comprising a one-piece jacket, a point core of relatively soft metal, a heel core of harder metal, and a partition integral with said jacket partially separating said cores.

2. A projectile comprising a one-piece jacket, a point core of relatively soft metal, a heel core of harder metal, and a closed fold in said jacket metal forming an inwardly extending annular transverse partition substantially separating said heel core from said point core.

3. A projectile comprising a one-piece jacket, a point core of relatively soft metal, a heel core of harder metal, and a closed fold in said jacket metal forming an inwardly extending annular transverse partition substantially separating said heel core from said point core and protecting said heel core against deformation on impact of the projectile against a target.

4. A projectile comprising a one-piece jacket, a point core of relatively soft metal, a heel core of harder metal, and a closed fold in said jacket metal forming an inwardly extending annular transverse partition substantially separating said heel core from said point core, said fold facilitating the disruption of the point section of the projectile upon impact while protecting the heel section.

5. A jacketed projectile comprising readily deformable point and difficultly deformable heel sections of substantially equal length, the junction of said sections comprising a fold in the jacket metal forming an annular transversely disposed partition of substantial width, whereby the projectile is caused to separate at said partition on impact against a target.

6. A projectile comprising a core and a jacket surrounding said core, said jacket comprising an integral inwardly extending closed fold forming an annular transversely disposed partition partially dividing said core into two sections each of substantial size, said fold extending inwardly for a substantial distance, whereby the sections are separated on impact of said projectile against a target.

7. A projectile comprising a core and a jacket surrounding said core, said jacket comprising an integral inwardly extending closed fold forming an annular transversely disposed partition partially dividing said core into two sections each of substantial size, said fold extending inwardly a substantial distance and determining a line on which said projectile separates on impact of the projectile against a target and likewise protecting the heel section from deformation on such impact.

8. A projectile comprising a heel core; a point core; a jacket substantially covering the exterior surface of both said cores; and a partition integral with said jacket extending inwardly therefrom a distance sufficient to substantially separate said cores and determine a line on which said projectile separates on impact against a target.

2. A projectile comprising a one-piece jacket, a point core of relatively soft metal, a heel core of harder metal, and a closed fold in said jacket metal forming an inwardly extending annular transverse partition substantially separating said heel core from said point core. 80

3. A projectile comprising a one-piece jacket, a point core of relatively soft metal, a heel core of harder metal, and a closed fold in said jacket metal forming an inwardly extending annular transverse partition substantially separating said heel core from said point core and protecting said heel core against deformation on impact of the projectile against a target. 85

4. A projectile comprising a one-piece jacket, a point core of relatively soft metal, a heel core of harder metal, and a closed fold in said jacket metal forming an inwardly extending annular transverse partition substantially separating said heel core from said point core, said fold facilitating the disruption of the point section of the projectile upon impact while protecting the heel section. 90

5. A jacketed projectile comprising readily deformable point and difficultly deformable heel sections of substantially equal length, the junction of said sections comprising a fold in the jacket metal forming an annular transversely disposed partition of substantial width, whereby the projectile is caused to separate at said partition on impact against a target. 100

6. A projectile comprising a core and a jacket surrounding said core, said jacket comprising an integral inwardly extending closed fold forming an annular transversely disposed partition partially dividing said core into two sections each of substantial size, said fold extending inwardly for a substantial distance, whereby the sections are separated on impact of said projectile against a target. 115

7. A projectile comprising a core and a jacket surrounding said core, said jacket comprising an integral inwardly extending closed fold forming an annular transversely disposed partition partially dividing said core into two sections each of substantial size, said fold extending inwardly a substantial distance and determining a line on which said projectile separates on impact of the projectile against a target and likewise protecting the heel section from deformation on such impact. 120

8. A projectile comprising a heel core; a point core; a jacket substantially covering the exterior surface of both said cores; and a partition integral with said jacket extending inwardly therefrom a distance sufficient to substantially separate said cores and determine a line on which said projectile separates on impact against a target. 130
